UNITED STATES PATENT OFFICE

ROY S. PEARSON, OF CHICAGO, ILLINOIS

TOOL

Application filed June 10, 1927. Serial No. 197,980.

This invention relates to improvements in tools particularly adapted for use in connection with the fitting of window lifts, strap hinges, door escutcheons, lock plates, etc., and one of the objects of my invention is the provision of a tool of this character which is specially adapted for use in temporarily retaining such articles in position while the fastening members are being attached there-
to or secured in position.

Another object of the invention is the provision of a tool of the above character which is readily adapted for use in scribing mortises by holding the hardware in place such as lock plates, strike plates, pivot plates and the like while the outline of the mortise is being marked off.

The invention has among its other objects the provision of devices of the kind described which are convenient, compact, durable and satisfactory for use wherever found applicable.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a longitudinal central section taken through a tool embodying my invention;

Fig. 2 is an end elevation of the improved tool shown in Fig. 1;

Fig. 3 is a section taken on line 7-7 of Fig. 1;

Fig. 4 is a section taken on line 8-8 of Fig. 1.

Upon referring to the drawings, it will be evident that I have shown a tool which em-

bodies my invention and is designated generally by the reference character 30. The tool 30 preferably comprises a handle 31 which may be formed of any suitable material and is preferably provided with a central bore 36, the bore 36 being formed with a portion 37 of reduced diameter which slidably journals one end of a pin 38 that has its other end slidably journaled in the larger portion of the bore 36. Screw-threaded into one end of the pin 38 is a pin 40 which is provided with a knurled head 41 at its outer end whereby it may be rotated to longitudinally displace the pin 38. As shown, the head 41 abuts against the outer side of an apertured disc 42 which is secured to the handle member 31 by screws 44, or the equivalent. A collar 45 rigidly secured to the pin 40 abuts against the inner side of the disc 42 and cooperates with the head 41 to prevent angular displacement of the pin 40. The pin 38 is held against rotation relative to the handle 31 by a lug 47 which rides in a slot 48 formed in the handle, the lug 47 being preferably formed integral with the pin 38. One end of the pin 38 is pointed and is preferably provided with screw-threads 49 so that the tool 30 may be used in substantially the same manner as similar tools. In practice, a double thread is preferably provided upon the pointed end of the pin 38. The pin 38 may be brought into a plurality of adjusted positions with respect to the handle 31 so as to have the screw-threaded end 49 project any desired distance from the handle member 31. This is advantageous in that, in some instances, it is only necessary to have the screw-threaded end 49 project a relatively small distance from the handle 31 as otherwise it would tend to mar the woodwork or to make too large holes therein. When the screw-threaded point 49 of the pin 38 is to be brought into an adjusted position with the handle 31, it is only necessary to manipulate the head 41 of the

pin 40 in such manner that the pin 38 will be longitudinally displaced in one direction or the other as the case may be. As illustrated in Fig. 1, the handle member 31 may 5 be reinforced by a metallic ferrule 31^a, or the equivalent.

When any of the above described devices is to be employed to temporarily secure a striker plate, escutcheon plate, or any other 10 piece of hardware to an object, the piece of hardware is correctly positioned upon the object and the threaded point on the tool is inserted through an aperture, or the equivalent, provided in the hardware, the threaded 15 point being screwed into the object. It will be readily understood that it is advantageous to have a double screw-thread as relatively few turns of the handle are required to drive the point into the object so that the hardware 20 will be clamped between the object and the shoulder provided at the base of the threaded point. Of course, the threaded point forms a hole in the object, in which hole, the screw, or the equivalent, may be quickly driven 25 when the threaded point has been withdrawn therefrom.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

35 What I claim as new and desire to secure by Letters Patent is:

1. A device of the kind described comprising a handle, a pin slidably mounted in the handle and provided with a pointed screw-threaded end adapted to project from said handle, a second pin rotatably mounted in the handle and screw-threaded into the first-mentioned pin whereby rotation of said second pin will result in longitudinal displacement of the first-mentioned pin, and means for preventing longitudinal displacement of said second pin.

2. A device of the kind described comprising a handle, a pin slidably mounted in the handle and provided with a pointed screw-threaded end adapted to project from said handle, a second pin rotatably mounted in the handle and screw-threaded into the first-mentioned pin whereby rotation of said second pin will result in longitudinal displacement of the first-mentioned pin, means for preventing the rotation of said first-mentioned pin, and means for preventing longitudinal displacement of said second pin.

60 3. A device of the kind described, comprising a handle having a passage therethrough with a groove communicating with said passage, a pin slidably mounted in said passage having a tool at one end thereof normally 65 projecting from said handle, a member en-

gageable in said groove for preventing rotation of said pin, a second pin rotatably mounted in said passage and screw-threaded into the first mentioned pin whereby rotation of said second pin will result in longitudinal displacement of said first pin, and means for preventing longitudinal displacement of said second pin.

In testimony whereof, I have hereunto signed my name.

ROY S. PEARSON.
